United States Patent Office.

JOSEPH A. RUFF, OF CAMBRIDGE, ASSIGNOR TO THE METALLIC COMPRESSION CASTING COMPANY, OF BOSTON, MASSACHUSETTS, ASSIGNOR TO RUSSELL & ERWIN MANUFACTURING COMPANY, OF NEW BRITAIN, CONNECTICUT.

Design No. 4,128, dated June 7, 1870.

DESIGN FOR A SASH-LIFT.

The Schedule referred to in these Letters Patent and making part of the same.

I, JOSEPH A. RUFF, of Cambridge, in the county of Middlesex and State of Massachusetts, have invented and produced a new and original Design for a Sash-Lift, of which the following is a specification.

The nature of my design is represented in the accompanying photographic illustration, to which reference it made.

I claim the design for a sash-lift, substantially as above set forth.

JOSEPH A. RUFF.
